UNITED STATES PATENT OFFICE

MORRIS SNEIDER, OF BALTIMORE, MARYLAND, ASSIGNOR TO THE MARYLAND COMPANY, OF BALTIMORE, MARYLAND, A CORPORATION

OVERALL GARMENT

Application filed February 21, 1930. Serial No. 430,353.

This invention relates to an overall garment of the type employing suspenders passing over the shoulders of the wearer and connecting the front and back portions of the garment, and the invention has for its primary object to provide, in a manner as hereinafter set forth, a garment of such class wherein the suspenders are secured at their rearward ends in a peculiar and novel manner, whereby the back portion of the garment may be disconnected from the suspenders in order that the back portion may be dropped without disarranging the position of the front portion or of the suspenders, and without removing the latter from the shoulders of the wearer.

A further object of the invention is to provide a garment of the class aforesaid in which is employed a novel type of suspender capable of being detachably secured at its rearward end to both the front and back portions of a garment.

With the foregoing and other objects in view the invention consists of the novel construction, combination and arrangement of parts as hereinafter more particularly described, and as illustrated in the accompanying drawing wherein is shown an embodiment of the invention, but it is to be understood that the description and drawing are to be taken as illustrative and that the invention is intended to be limited only by the scope of the claims hereunto appended.

In the accompanying drawing in which like numerals are employed to designate like parts throughout the several views:—

Figure 1 is a front elevation of a garment in accordance with this invention.

Figure 2 is a rear elevation thereof showing the back or seat portion disconnected from one of the suspenders.

Figure 3 is a section taken on line 3—3 of Figure 1.

The garment illustrated in the accompanying drawing is designed particularly for wear by women although it is contemplated that the invention will be applied also to overall garments adapted to be worn by men and children. The garment as shown includes a main body designated generally

by the numeral 1 which is formed with a pair of depending legs 2. The body 1 includes a front portion 3 formed or provided at its upper edge with a front waist band 4, and a back or seat portion 5 formed or provided at its upper edge with a back waist band 6. At the sides thereof the front and back portions of the body are stitched together from the lower edges of the portions to points removed from the waist bands 4 and 6, such points being designated by the numeral 7. Adjacent each end of the waist band 4, the latter is unattached to the front portion 3 whereby a triangular flap portion 8 is provided which is free of connection with both the waist band 4 and back portion 5. The flap portion 8 is bent or turned back and secured to the forward face of the front portion 3. Each of the flaps 8 is provided with a button 9 for the purpose of ornamentation. Spaced from each end thereof the waist band 4 is provided with a suitable buttonhole 10.

Secured to the inner face of the front portion, 3, are a pair of pocket forming members 11 which project outwardly beyond the bends of the flaps 8. The upper edge of each member 11 is secured to the waist band 4, and the outer side edge thereof extends in continuation of an end face of the waist band 4 and of the stitched side edges of the front portion 3 and back portion 5. Each pocket forming member 11, in connection with the inner face of the front portion 3, provides a pocket the entrance of which is disposed at the folded edge of a flap 8. In horizontal alignment with the ornamental buttons 9, each pocket forming member 11 is provided with a button-hole 12.

Spaced from each end thereof, the rear waist band 6 is formed with a series of button-holes 13, in the present instance three of such button-holes being provided adjacent each end of the waist band. Adjacent each end of the waist band 6 a button 14 is provided which is disposed in horizontal alignment with the button-holes 13. The waist band 6 is of greater length than the waist band 4 and the end faces thereof are disposed in continuation of the side edges of that portion of the back portion 5 which is disposed above the 100

points of connection 7 between the front and back portions. At each side thereof, from a point 7 to and including an end portion of the waist band 6, the back portion 5 is in-turned to provide a flap 16 which is provided with a button 17. The buttons 17 and 14 respectively are adapted to be engaged with the button-holes 12 and 10.

Formed with or secured to the front waist band 4, and extending upwardly therefrom, is a bib 18 which is provided centrally thereof with a suitable pocket 19, and which is provided adjacent each upper corner thereof with a button hole 20, each of which is adapted to have secured thereto a suspender 21. Each suspender 21 is of elongated, tapered formation having its smaller end disposed forwardly and provided with a button 22 for engagement with a button-hole 20 in the bib 18. At the wider-rearward end thereof, each suspender is formed with an enlargement 23 which is provided with a series buttons 24 for engagement with the button-holes 13 spaced from one end of the rear waist-band 6. The enlargement 23 of each suspender is formed with a lateral projection 25 which is adapted to be curved around a side edge of the bib 18, and which is provided with a button-hole 26 for engagement with a button 27 secured to the forward face of the bib 18 adjacent a lower corner thereof.

When it is desired to drop the back or seat portion 5, the buttons 24, 14 and 17 respectively are disengaged from the button-holes 13, 10 and 12 respectively which entirely frees all of the back portion 5 which is located above the points of connection 7 between the front and back portions. Owing to the engagement of the buttons 27 with the button-holes 26, the rearward ends of the suspenders 21 are maintained in proper position with the suspenders passing over the shoulders of the wearer and with the front portion of the garment, including the bib 18, in proper wearing position.

It is thought that the many advantages of a garment in accordance with this invention will be readily apparent, and although the preferred embodiment of the invention is as illustrated and described, it is to be understood that changes in the size, shape and arrangement of parts may be resorted to, so long as such changes fall within the scope of the invention as defined in the appended claims.

What I claim is:

1. An overall garment comprising, a front portion and a back portion connected at their sides to provide the body of the garment, the connections between said portions adjacent the tops thereof being detachable, a bib extending upwardly from the front portion, and a pair of tapered suspenders having their narrower ends connected with the bib and having their wider ends formed with enlargements

detachably connected with the back portion adjacent the upper edge of the latter, said enlargements having lateral projections bent around the side edges of the bib and detachably secured to the forward face thereof. 70

2. An overall garment comprising, a front portion and a back portion providing the body of the garment, said portions being permanently connected at their sides to points removed from their upper edges, a pair of folded flaps bent back against the outer face and formed at the upper corners of said front portion, a pair of pocket forming members secured to the inner face of the front portion projecting laterally beyond the bends of 75 said flaps, said pocket forming members being detachably connected to said back portion, a bib extending upwardly from the front portion, and a pair of tapered suspenders having their narrower ends connected with the bib and having their wider ends formed with enlargements detachably connected with the back portion adjacent the upper edge of the latter, said enlargements having lateral projections bent around the side edges of the 80 bib and detachably secured to the forward face thereof. 85

3. An overall garment comprising, a front portion and a back portion providing the body of the garment, said portions being permanently connected at their sides to points removed from their upper edges, a front waist band formed at the upper edge of the front portion, a rear waist band formed at the upper edge of the back portion, a pair of pocket 95 forming members secured to the inner face of the front portion, said pocket forming members being detachably connected adjacent their outer side edges to said back portion, the ends of said rear waist band being detachably connected with the ends of said front waist band, a bib extending upwardly from the front waist band, and a pair of 100 tapered suspenders having their narrower ends detachably connected with said bib and 110 having their wider ends formed with enlargements detachably connected with said rear waist band, said enlargements having lateral projections bent around the side edges of the bib and detachably secured to the forward 115 face thereof. 120

In testimony whereof, I affix my signature hereto.

MORRIS SNEIDER.
